UNITED STATES PATENT OFFICE.

JAMES A. CHEWNING, OF SIKESTON, MISSOURI.

WINDOW SCREEN.

Application filed April 24, 1925. Serial No. 25,688.

The invention relates to improvements in window screens.

The object of the present invention is to improve the construction of window screens and to provide a simple, practical and efficient window screen of strong, durable and comparatively inexpensive construction equipped with a metal frame and adapted for use on various kinds of windows.

Another object of the invention is to enable the window screens to be readily assembled and to provide means whereby the wire screen material may be easily stretched and secured in the metal frame.

Another object of the invention is to enable the wire screen material to be readily replaced when worn without discarding the metal frame.

Another object of the invention is to provide a metallic window screen adapted for use on passenger coaches and capable of being readily inserted in place when a car window is raised.

It is also an object of the invention to provide a window screen adapted to be readily hinged at the top of the window to swing outwardly therefrom when access to the exterior is desired.

With these and other objects in view the invention consists in the construction and novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:

Figure 1 is a side elevation of the metallic window screen constructed in accordance with this invention, a portion of the metallic frame being in section.

Fig. 2 is an edge view of the same.

Fig. 3 is an enlarged horizontal sectional view on the line 3—3 of Fig. 1.

Fig. 4 is an enlarged detail sectional view on the line 4—4 of Fig. 1.

Fig. 5 is a detail perspective view of one of the clamps for holding the wire screen material.

Fig. 6 is a detail view of the crimping tongs.

Fig. 7 is an elevation of a window screen showing another form of the invention.

Fig. 8 is an edge view of the same.

Fig. 9 is a detail view of a portion of the hook for removing the clamps when it is desired to replace the wire screen material.

Referring now particularly to Figs. 1 to 4 inclusive of the drawings in which is illustrated a metallic window screen designed particularly for use on railway coaches, the window screen comprises in its construction a metallic frame composed of vertical side members 1 and connecting horizontal top and bottom members 2 and 3. Each of the frame members is constructed of suitable sheet metal which is bent along longitudinal lines to form a channel having longitudinal flanges 4 at the inner side. The channel frame member consists of parallel sides, and connecting outer portion and the said flanges 4 which are arranged in parallelism with the outer portion as clearly shown in Figs. 3 and 4 of the drawings. The horizontal top and bottom channel members are cut away at the flanges 4 and the parallel outer portion to provide terminal overlapping ears 5 which are secured to the terminal portions of the side channel members by bolts 6 having countersunk heads equipped with nuts 7 provided with tubular interiorly threaded portions 8 into which the threaded portions of the bolts extend. The metallic screen frame is equipped at the bottom with an extensible bottom member 9 composed of two sides, a connecting portion and provided in its sides with slots 10 receiving the lower bolts and adapted to permit the extension member 9 to slide inwardly and outwardly with respect to the bottom frame member. This will adapt the window screen particularly for use in passenger coaches and similar conveyances and will obviate the necessity of employing the hinged sectional screen usually required for such windows. Suitable springs may be employed for holding the bottom member 9 normally in an extended position. The bottom members will engage the window sill between the parting strip and the blind stop but any suitable means may, of course, be employed for retaining the extensible frame in position.

The window screen is equipped with a single, continuous sheet 11 of wire screen material and the marginal portions extend into the channel members of the frame be-

tween the adjacent inner edges of the flanges 4 which are spaced apart to permit the screen material to enter the frame members. The marginal portions of the screen material 5 is held within the frame members by clamps or binding elements 12 consisting of narrow strips of sheet metal bent to form a U-shaped loop 13 and terminal laterally extending flanges 14. The loop receives the 10 marginal portion of the screen material and the lateral extending flanges abut against the longitudinal flanges of the frame members. The U-shaped portion 13 is crimped into engagement with the screen material by 15 a tool 15 in the form of a pair of tongs having jaws 16 provided at their contacting faces with triangular lugs 17 and corresponding recesses 18. A pair of the lugs 17 is preferably employed and are reversely arranged as clearly illustrated in Fig. 6 to 20 provide the reversed crimps shown in Fig. 3 of the drawing. In small screens a single lug may be employed.

In assembling the screens the clamps 12 25 are applied to two of the marginal edges of the screen and are placed in the respective frame members and the other frame members are then assembled to complete the frame. The frame members at the marginal 30 edges of the sheet of material to which the clamps have not yet been applied are provided with openings 19 through which the jaws 16 of the tool 15 with a clamp 12 may be passed and the clamp placed on the screen 35 material and crimped. The screen material during this operation is stretched with an ordinary pair of pliers having jaws sufficiently small to pass through the openings 19. The screen material may in this manner stretch to the desired tension and the 40 clamps may be applied at intervals for securely holding the screen material under such tension. After a clamp has been applied the jaws 16 may be moved laterally 45 out of engagement with the clamp and sufficiently beyond the same to enable the tool to be removed from the opening 19 without affecting the tightness of the clamp. Should it be desired to apply new screen material 50 the clamps may be readily removed by means of a hook 20 which may be introduced through the openings 19 and engaged with the clamps for spreading the sides of the loop 12. The bill 21 of the hook 20 is 55 beveled laterally to enable it to be readily engaged with the clamps.

In Figs. 7 and 8 of the drawings is illustrated another form of the invention which is adapted for larger windows than the 60 screen shown in Figs. 1 to 4 inclusive. The screen of this form of the invention is composed of side channel members and top and bottom channel members similar to that heretofore and in addition has central transverse braces 22 provided with side flanges

23 which extend across the space between the side frame members and terminate thereat. The side flanges extend inwardly to the screen material and the terminal portions are secured to the side frame members by 70 bolts similar to those heretofore described.

The screen is equipped at the top with hinged elements 23 secured at their lower portions to the screen frame by the upper corner bolts thereof and having outwardly 75 offset upper portions 24 provided with slots 25 adapted to be engaged with hooks or other hinged elements for supporting these window screens at the top of a window. The hinged elements are angularly bent at their 80 centers to offset the upper portion 24 as clearly shown in Fig. 8 of the drawings. The screen frame is equipped at the bottom with a hook 26 hinged to an eye 27 of the bottom frame member and adapted to engage a suitable eye 28 of a window sill. When the hook is disengaged the screen is 85 adapted to be swung outwardly to afford access to the exterior.

What is claimed is:

1. A screen, including a metallic frame composed of frame members of channel form provided at their inner sides with inwardly extending flanges, a sheet of screen material having its marginal portions extending between the said flanges and clamps arranged at intervals and consisting of loops embracing the marginal portions of the said sheet and crimped thereon interiorly of the frame after the said screen material is placed in 100 position in the frame and having laterally bent terminals abutting against the flanges of the frame members.

2. A screen including a metallic frame composed of frame members of channel form provided at their inner sides with inwardly extending flanges, a sheet of screen material having its marginal portions extending between the said flanges and clamps arranged at intervals and consisting of loops embracing the marginal portions of the said sheet and crimped thereon in the plane of the screen material interiorly of the frame after the said screen material has been placed in 110 position in the frame and having laterally bent terminals abutting against the flanges of the frame members, said frame being provided with openings of a size to permit the clamps and a crimping tool to be passed through them to enable clamps to be crimped 120 from the exterior of the frame after the same has been assembled.

3. A screen including a metallic frame composed of channel frame members having inwardly extending longitudinal flanges in the sides spaced apart to form slots, a sheet of screen material having its marginal portions extending through the slots into the frame members, clamps consisting of narrow strips of metal bent into approximately 130

U-shape to embrace the marginal portions of the screen material and having their terminals bent laterally to form lugs for abutting against the flanges of the screen frame, said 5 clamps being provided with reversely arranged approximately triangular crimps securing the U-shaped portions to the screen material, said crimps being formed interiorly of the frame after the screen material has 10 been placed therein and being arranged in the plane of the screen material.

4. A screen including a metallic frame composed of channel frame members having inwardly extending longitudinal flanges in 15 the sides spaced apart to form slots, a sheet of screen material having its marginal portions extending through the slots into the frame members, clamps consisting of narrow strips of metal bent into approximate U-

shape to embrace the marginal portions of the screen material and having their terminals bent laterally to form lugs for abutting against the flanges of the screen frame, said clamps being provided with reversely arranged approximately triangular crimps securing the U-shaped portions to the screen material formed interiorly of the frame in the plane of the screen material after the same has been placed in the frame, certain 20 of the frame members being provided at the 25 outer sides with openings of a sufficient size to permit the passage of the clamps and a crimping tool to permit clamps to be crimped exteriorly of the frame after the same has 30 been assembled. 35

In testimony whereof I affix my signature.

JAMES A. CHEWNING.
